(57) **CLAIM**

The ornamental design for a angled pliers, as shown and described.

DESCRIPTION

FIG. 1 is a front perspective view of angled pliers; FIG. 2 is a front elevation view of angled pliers; FIG. 3 is a rear elevation view of angled pliers; FIG. 4 is a right-side view of angled pliers; FIG. 5 is a left-side view of angled pliers; FIG. 6 is a top view of angled pliers; FIG. 7 is a bottom view of angled pliers; FIG. 8 is a rear perspective view of angled pliers; and, FIG. 9 is an alternative perspective view of angled pliers. The broken lines in the drawings illustrate portions of the angled pliers that form no part of the claimed design.
